METHOD AND APPARATUS FOR APPLYING MATERIALS TO SURFACES

Louis G. Merritt and Ericsson H. Merritt, Lockport, N. Y., assignors, by mesne assignments, to Laminating Patents Corporation, Seattle, Wash., a corporation of Delaware

Application June 5, 1931, Serial No. 542,257

42 Claims. (Cl. 91—43)

This invention relates to methods and apparatus for disseminating powdered materials, and, more particularly, for the application of powdered materials to surfaces of articles such, for example, as veneer sheets and the like.

An object of the invention is to provide improved methods and apparatus of the character under consideration.

Another object is to provide a method whereby powdered materials may be applied to surfaces of articles in a particularly uniform manner.

A further object is to provide a method whereby powdered materials containing particles of varying size may be readily, effectively and uniformly applied to surfaces of articles, and particularly to surfaces of moving articles.

Another object is to provide apparatus of the character under consideration for readily and effectively applying powdered materials to the surfaces of articles.

Another object is to provide apparatus of the character under consideration whereby powdered materials may be applied to the surfaces of articles in a particularly uniform manner.

Another object is the provision of improved means for applying powdered materials to the surfaces of moving articles.

Another object is to provide means for effectively applying to the surfaces of articles a powdered material containing particles of varying size.

An additional object is the provision of apparatus of the character indicated which is relatively simple in construction, which can be readily assembled, and in which parts may be readily removed for repair and replacement; which will operate in a particularly uniform manner, and which will efficiently accomplish the purposes for which it is intended.

Other objects of the invention will in part be obvious and will in part appear hereinafter.

The invention accordingly comprises the several steps and the relation and order of one or more of such steps with respect to each of the others, and the apparatus embodying features of construction, combinations of elements and arrangement of parts, all as exemplified in the following detailed disclosure, and the scope of the application of which will be indicated in the claims.

For a fuller understanding of the nature and objects of the invention reference should be had to the following detailed description taken in connection with the accompanying drawings, in which:

Figure 1 is a view of a form of apparatus exemplifying the invention in vertical section along the line 1—1 in Fig. 3;

Fig. 2 is an enlarged detail showing of the central portion of Fig. 1;

Fig. 3 is a view at right angles to Fig. 1 in vertical section along the line 3—3 in Fig. 4; and

Fig. 4 is a side view of the apparatus.

The problem of applying powdered material to surfaces of articles, as, for example, in applying coating materials in powdered form or in applying powdered adhesive materials to surfaces to be glued has proved a matter of considerable difficulty, particularly in instances wherein an especially high degree of uniformity in the spread of the powdered material on the surfaces was desired. That there are many such instances will be readily apparent when it is considered that the appearance of coated articles often depends upon the uniformity of the coating applied, and that in the gluing art the strength of the bond is often dependent upon a high degree of uniformity of spread. Again, where the coating material or the adhesive material is of a relatively expensive nature the desirability of limiting the spread to a minimum throughout the entire area of the surface to which the material is applied will be readily apparent.

With the foregoing and other ends in view, the present invention contemplates the provision of methods and means whereby various factors having tendencies away from a maximum of uniformity may be desirably controlled and various difficulties overcome.

The invention provides methods and means in the performance and use of which more or less of a variety of desirable steps may be performed in a desired sequence. While in the more specific aspects of the invention, all, or at least several, of such steps will be performed, the invention in its broader aspects is not limited to the performance of a method involving, or the use of apparatus for performing, any particular number or sequence of such steps.

As an example of a method such as contemplated by the invention reference may be had to a procedure which may be conducted by the apparatus hereinafter described, and which involves continuously disseminating above moving articles, such as veneer sheets or the like, a stream of particles substantially as wide as the sheets, breaking up the stream so as to assure that the particles will not be associated in globules or in minor streams, and directing a current of air

against the broken-up stream, so as to carry particles evenly and regularly onto the moving sheet. Where the particles to be disseminated are contained in a receptacle, it is desirable to replenish the particles continuously and preferably at a controlled and substantially uniform rate, and it is also desirable that the particles to be supplied be agitated in many instances.

One form of apparatus such as contemplated by the invention and such as utilizable in carrying out the methods contemplated by the invention is exemplified in the drawings.

This apparatus comprises a container 10 for holding a mass of powdered material, across the bottom of which there extends a portion of an endless belt 11 of foraminate construction. Such a belt may desirably be formed of cloth or wire-mesh and is adapted to be supported on a plate 12 which is preferably formed of rubber firmly vulcanized to a plate 13 carried by the framework of the machine. The belt is adapted to pass into the container under a bar 14 on a side plate 15 and after travelling beneath a mass of particles 16 in the container and receiving such particles in its interstices passes out of the container between the bevelled end 17 of the plate 12 and a rubber cylinder 18 on a roller 19. In order to assure that the powdered material will drop out of the interstices of the belt as the latter clears the end 17 of the plate 12, there is provided a vibrator roller 20, the periphery of which is formed with protuberances 21 which are adapted during rotation to jar the belt which is held tight by means hereinafter to be exemplified. In order to assure that only the particles within the interstices of the belt will be carried from the container, the roller 19 is rotated, preferably relatively slowly, in a direction such that its surface will move inwardly and upwardly as it enters the container, and in order to prevent particles from being carried out of the container by the roller, there is provided a doctor bar 22 carried on arms 23 pivoted on studs 24 on the walls of the container. The doctor bar 22 accordingly is held by gravity against the surface of the cylinder 18 to form an effective closure for the container at this point.

In the use of a large number of powdered materials including many of the adhesive materials which are desirable for use in the formation of plywood and similar procedures the particles of the material will have a tendency more or less to cohere, and for the purpose of breaking up globules thus formed, as well as for other purposes including the smoothing out of any unevenness in the film or stream of particles, a suitable break-up element is disposed in the path of movement of the particles. As exemplified, this element consists of a rotatable roll 25 having its downwardly moving side in the path of the stream of particles falling from the points where the belt leaves the edge 17 of the support 12. It is to be noted that the particles tend to follow an arcuate course along the side of this roll due to the natural induction of the air surrounding the roller.

The difficulties in providing a spread having a high degree of uniformity attend especially a procedure wherein the size of the particles to be sprayed is irregular, i. e. where the material to be spread consists of both coarse and fine particles. This is not only the case wherein a mixture of two materials of relatively different size is utilized; but also in all cases where it is desired to avoid the necessity of using a powder of which

the particles are of substantially the same size, with the attendant expense and waste involved in the provision of such a powder.

In order to avoid the tendency of casual air currents to vary the movement of the particles beneath the roll 25 and to separate the finer particles from the coarser as well as to dissipate certain of the finer particles, and also in order to guide the particles in an even and substantially uniform manner in a desired direction toward the surface to be coated there is provided means for ejecting a jet of air against the stream at a point which preferably is somewhat beneath the break-up roll. In the present instance this means comprises a nozzle-member 27 formed with a nozzle portion composed of closely spaced plates 28 and 29, the adjacent surfaces of which are inclined downwardly so as to direct a current of air, just under the roller 25, in a direction transverse to the stream of the falling particles and downwardly, with the result that these particles will assume courses generally between a sharply inclined plane and a less inclined plane above the same, the heavier particles following a course adjacent the sharply inclined plane, and the lighter particles following a course adjacent the less inclined plane. A current of air is carried into the nozzle member 27 from a blower 31 at one side of the machine through a conduit comprising opening 31a, dampening chamber 31b, and opening 32. The current is smoothed out to provide an even outward flow throughout the length of the space between the plates 28 and 29 by means of baffle members 32a extending transversely of the nozzle member 27.

The current of air issuing from between the members 28 and 29 provides a moving inclined support on which the particles "toboggan" to the surface on which they are to be spread.

It is desirable that the velocity of this air-current be just enough to overcome the tendency of natural or prevailing air-currents to influence the falling powder. For example, under conditions where no extraneous air currents are set up outside the machine a desirable velocity, at the point where the air leaves the nozzle portion may be about 120 feet per minute for 200 mesh particles, may be from 150 to 200 feet per minute for material 90% of which would pass through 100 mesh and 40% of which would pass through 150 mesh; and may be 230 feet per minute for material all of which would pass through 80 mesh and 30% of which would pass through 150 mesh and which contained a relatively small percentage of fines. The foregoing figures are "apparent" velocities, based upon readings of an anemometer ("Tyco" No. A105, outside diameter of the blade circle $3\frac{1}{8}$ inches, inside diameter $1\frac{1}{4}$ inches, width of blade one inch on outside circle and $\frac{1}{4}$ inch on inside circle) placed with its center against the lip (which was $1\frac{1}{8}$ inches wide) at a point between the ends of the orifice (which was .140 inch across and several feet long). It will be understood that the actual velocities are higher. The particles referred to are those of an average weight glue powder (about 35 pounds per cubic foot of powder). As will be seen from the foregoing the air current should be varied in the spreading of materials wherein the individual particles have different weights; a higher velocity being used with powders having a greater weight per particle.

The surfaces of the articles upon which the particles are to be received may be arranged in any desired manner for the reception of these

particles. Preferably, however, they are moved through the path of flow of the particles, as, for example, on a suitable conveyor. In the present instance, there is provided a conveyor 33 arranged 5 to move sheets 34 of veneer or the like along a plane which is relatively close to the roll 25 and through the cloud of particles indicated at 30.

The surfaces may be moved in any desired direction with respect to the direction in which the 10 particles are carried by the air current. In the present instance, the movement of the sheets is exemplified as being in a direction opposite to the horizontal component in the direction of movement of the particles. Such an arrangement is 15 of advantage in certain instances, as, for example, when relatively non-coherent particles are being applied to a relatively adherent surface, for instance, a moist surface, since the finer particles will first contact with the adherent surface. 20 Effective results are secured, however, in a large number of instances when the direction of movement of the sheets is the same as the horizontal component of the direction of movement of the particles.

25 It will accordingly be seen that the present invention is of value in carrying out various gluing methods, such, for example, as that disclosed in the application of Theodore Williams Dike, filed February 28, 1931, Serial No. 518,944, and which 30 has matured into Patent Number 1,869,957, issued August 2, 1932.

Powdered material may be supplied to the container 10 in any suitable manner, but is preferably supplied thereto at a uniform rate and in 35 controlled amounts. To this end there is provided at a point above the container a trough-like container 35, the bottom wall of which is provided by a plate 36 having formed at one side of its center line a series of openings 37, and above 40 the plate 36 there is disposed an adjustable plate 38 having a series of similar openings 39 adapted to coincide with the openings 37. For the adjustment of this plate there is provided a hand-wheel 40 carrying a screw 41 extending into a 45 threaded opening in a bar 42 secured to the plate 38. Accordingly, by the movement of the hand-wheel the size of the channels provided by the openings 37 and 39 may be reduced to any desired extent.

50 Powdered material is supplied to the trough-like container from a hopper 43, and movement of the powdered material past the openings, as well as continuous agitation of the material in the trough-like container is assured by causing a continuous circulation of the material as by means 55 of a pair of parallel oppositely-moving spiral conveyors 44 and 45.

The endless belt 11, which may be supported and driven in any suitable manner, is, as exemplified, carried from the vibrating roll 20 over a 60 roll 46 and thence over rolls 47, 48 and 49. Prior to passing into the container, the belt passes over a roll 50. Between the rolls 49 and 50 it passes inwardly about a tensioning roll 51, the shaft of 65 which is journalled in boxes 52 and 52', which are adapted to slide between track members 53 and 54, and 53' and 54', respectively. A movement of the roll to effect the tensioning of the belt may be caused by the adjustment of a tension rod 55. It 70 is to be noted that in the construction indicated the roll 51 may be readily slipped in place after the endless belt has been positioned over the other rolls and may readily be removed merely by loosening a securing means, such as the bolt and nut attachment shown at 56. The tension rods 55 are

suitably fitted at their outer end to pass through tension-adjusting wheels 57, which, acting through spaced sleeves 58, serves to bear against an equalizer bar 59. A weighted tension lever 60 is suitably connected to the central portion of the equalizer bar 59 as through link pins 61, 62 and 63, link 64 and clevis 65. A shaft 66 is disposed to pass between portions of the framework. The tension weight 67 is attached to the lever 60 by means of gibs 68 in a manner which allows for a wide range of movement of the weight to obtain the screen tension desired in any particular instance.

It will be observed that the exemplified apparatus comprises a measuring device—the travelling belt—, means to discharge the measured amounts of material from the measuring device in a uniform film or curtain—the vibrator roller—, means to separate aggregations of particles in the falling film or curtain into individual particles—the break-up roller—, and means whereby the individual particles are conducted or guided through a free space above the surface of moving articles—the air delivery means. A combination of such elements provides a particularly effective means for the spreading of powdered materials and especially satisfactory results have been found to be obtained by the use of apparatus similar to that exemplified. However, in certain of its broader aspects the invention contemplates 100 the provision of a variety of forms of apparatus embodying one or more of the types of elements set forth and adapted for use in various ones of a wide number of procedures.

The exemplified apparatus embodies a form of 110 conveyor which has been found particularly desirable for use in methods such as those under consideration. As exemplified, the conveyor 33 comprises a single endless cable 70 extending back-and-forth over drums 71 and 72 which are 115 provided with annular grooves 73 for the reception of the cable. During a portion of its run from one end of the drum 72 to the other end of the drum 71, the cable passes about sheaves 74 and 75 which are carried, respectively, on brackets 76 and 77. The brackets are adjustably mounted between rails 78 and 79, and 80 and 81, respectively, so that they may be slid to a position to suitably tension the cable. They are held in 120 adjusted position by suitable means such as the 125 nuts 82 and 83, respectively. Suitable means (not shown) may be provided for driving one or the other of the drums 71 and 72; such means may include variable speed mechanism of any well-known type, if desired.

Suitable means are likewise provided for driving the other movable elements of the apparatus. In this connection it is to be noted that the foraminous belt or screen preferably moves at a relatively slow speed, in certain instance, for 135 example, two, three or four feet per minute. It is desirable, in many cases, that variable speed mechanism be provided in the driving means for this belt so that the quantity of material disseminated may be readily controlled.

In the present instance there is provided a driving motor 106 from the shaft of which rotative motion is transferred by a sprocket 107, a chain 108, and a sprocket 109 to the constant-speed shaft 110 of a variable-speed mechanism 140 indicated generally at 111 and which may be of any well-known type, as, for example, the cone-and-belt type. On the variable-speed shaft 112 of the variable-speed mechanism there is carried a gear 113 meshing with a reduction gear 114 145

carried for the sake of simplicity of construction on the shaft 110, in the present instance, but freely movable thereon. Carried on the gear 114 is a small gear 115 meshing with a secondary 5 reduction gear 116 which carries a sprocket 117 connected by a chain 118 with a sprocket 119 rotatably mounted on a stud 120. Carried on the sprocket 119 is a smaller sprocket 121 from which a chain 122 extends to a sprocket 123 carried on 10 the shaft of the drive roll 49 for the screen. There is also carried on the sprocket 119 a sprocket 124 from which a chain 125 extends over a sprocket 126 carrying a gear 128 meshing with a gear 129 mounted on the shaft of the doctor 15 roll 19.

The shaft 110 also carries a sprocket 130 from which a chain 131 extends to a sprocket 132 rigidly keyed to one of the ends of the break-up roll 25. A second sprocket 133 rigidly mounted 20 beside the sprocket 132 imparts its motion through a chain 134 to a sprocket 135 rigidly fixed to one of the ends of the vibrator roll 20.

The drive for the spiral conveyors is an independent unit in the present instance, due to the 25 somewhat remote locations of these conveyors. A motor 136 supported on a bracket 137 imparts its motion through a coupling 139 to a worm gear speed reducer 140 from which the reduced 30 rotative speed is further conveyed to the spiral conveyors through a sprocket 141, a chain 142 and a sprocket 143.

The term "dry air" as used herein is intended to refer to air to which droplets of moisture have not been added.

5 Since certain changes in carrying out the above method and in the constructions set forth, which embody the invention may be made without departing from its scope, it is intended that all matter contained in the above description or 0 shown in the accompanying drawings shall be interpreted as illustrative and not in a limiting sense.

It is also to be understood that the following 5 claims are intended to cover all of the generic and specific features of the invention herein described, and all statements of the scope of the invention which as a matter of language might be said to fall therebetween.

Having described our invention, what we claim 0 as new and desire to secure by Letters Patent is:

1. The method of applying powdered material to a surface, which comprises causing a movement of the surface, directing generally toward said surface a stream of particles at a rate substantially just sufficient for the desired coating of the moving surface and directing against said stream a current of dry air moving in a direction transverse to said stream and toward said surface and so regulated that material quantities of particles will not be removed from said surface by said current.

2. The method of applying powdered material to a surface, which comprises causing a movement of the surface, directing generally toward 5 said surface a stream of particles at a rate substantially just sufficient for the desired coating of the moving surface and directing against said stream a current of dry air moving in a direction transverse to said stream and opposite to the direction of movement of said surface and so regulated that material quantities of particles will not be removed from said surface by said current.

3. The method of applying powdered material to a surface, which comprises directing a curtain of particles in a given direction, breaking up any

globules or independent streams of particles embodied in said curtain, moving a surface beneath said curtain, directing against said curtain a current of dry air in a direction generally transverse to said stream and toward the surface to be coated and in a manner such that substantially all the particles directed toward said surface will be evenly deposited on said surface. 80

4. The method of applying powdered material to a surface, which comprises causing a relative movement of a container for powdered material and a surface to be coated, supplying a continuous controlled flow of particles of material to said container, withdrawing material from said container at a uniform rate substantially just sufficient for the desired coating of a surface during such movement, directing the withdrawn particles in a stream toward the surface of an article to be coated, and guiding the flow of particles toward said surface by directing against said stream a current of dry air so regulated that material quantities of particles will not be removed from said surface by said air current. 85 90 95

5. Apparatus for applying powdered material to surfaces comprising means continuously to measure out uniform quantities of powdered materials and to uniformly discharge measured amounts of material from the measuring device, means to separate the individual particles of the material so discharged, and means for directing a current of dry air upon the separated particles whereby said particles are guided to a surface to be glued. 100 105

6. Apparatus for applying powdered material to surfaces, comprising means including an endless foraminous belt to disseminate a powdered material, and means to guide the disseminated material toward the surface of an article. 110

7. Apparatus for applying powdered material to surfaces, comprising means including an endless foraminous belt to disseminate a powdered material, and means to direct a current of air relative to the disseminated material to guide the same toward the surface of an article. 115

8. Apparatus for applying powdered material to surfaces, comprising means to disseminate a powdered material, said means including an endless foraminous belt and a rotary vibrator member, and means to guide the disseminated material toward the surface of an article. 120 125

9. Apparatus for applying powdered material to surfaces, comprising means providing a container for materials, means including an endless belt for withdrawing materials from said container, means including a vibrator member to remove withdrawn materials from said belt, and means to direct the withdrawn materials against a surface to be coated. 130

10. Apparatus for disseminating powdered materials, comprising an endless foraminous belt, means to cause said belt to receive powdered material in the openings thereof, and means to remove powdered materials from the openings in said belt. 135

11. Apparatus for disseminating powdered materials, comprising an endless foraminous belt, means to cause the belt to receive powdered material in the openings thereof, and means to vibrate the belt to cause the removal of particles from said openings. 140

12. Apparatus for disseminating powdered materials, comprising an endless foraminous belt, means for maintaining a mass of material above a portion of said belt, means to drive said belt, and means to cause materials received in the 145 150

- openings of said belt to fall therefrom at a given point in its path.
13. Apparatus for disseminating powdered materials, comprising an endless foraminate belt, a supporting surface for a portion of said belt, means to provide the side-walls of a container above said supporting surface, means to drive said belt, and means to cause the material received by said belt in the openings thereof to fall therefrom at the point where said belt leaves said supporting surface. 80
14. Apparatus for disseminating powdered materials, comprising an endless foraminate belt, a supporting surface for a portion of said belt, means to provide the side-walls of a container above said supporting surface, said means including a doctor roller disposed with its periphery adjacent one edge of said supporting member, means to drive said belt, and means to cause the material received by said belt in the openings thereof to fall therefrom at the point where said belt leaves said supporting surface. 85
15. Apparatus for disseminating powdered materials, comprising an endless foraminate belt, a supporting surface for a portion of said belt, means to provide the side-walls of a container above said supporting surface, said means including a doctor roller disposed with its periphery adjacent one edge of said supporting member, means to drive said belt, means to drive said doctor roller in a direction such that its periphery moves rearwardly with respect to said endless belt, and means to cause the material received by said belt in the openings thereof to fall therefrom at the point where said belt leaves said supporting surface. 90
16. Apparatus for applying powdered materials to surfaces including means to move a surface in a given path, means to disseminate a powdered material, and means to provide a low velocity current of dry air to direct the powdered material upon said surface. 95
17. Apparatus for applying powdered materials to surfaces including means to move a surface in a given path, means to cause a flow of material in a curtain toward said path of movement, and means to direct against the flowing material a current of dry air moving transversely to the curtain and toward said path of movement. 100
18. Apparatus for applying powdered materials to surfaces including means to move a surface in a given path, means to cause a continuous flow of powdered material in a given plane, means interposed in the path of flow of said material for breaking up any aggregations of particles and delivering the particles in a single stream, and means for directing a current of dry air against the delivered stream whereby the particles may be directed against the moving surface. 105
19. Apparatus for applying powdered materials to surfaces including means to move a surface in a given path, means to cause a continuous flow of powdered material in a given plane, means interposed in the path of flow of said material for breaking up any aggregations of particles and delivering the particles in a single stream, and means to direct a slowly moving current of dry air against the said stream to direct the particles against a surface. 110
20. Apparatus for applying powdered materials to surfaces including means to move a surface in a given path, means to cause a flow of material in a curtain toward the path of said movement, and means to direct against the flowing material a current of dry air moving in a 115
- direction toward the moving surface and opposite to the direction of movement thereof, said directing means being arranged so that the air current while moving in said direction contacts said flow on its way to said path. 120
21. Apparatus for applying powdered materials to surfaces including means to move a surface in a given path, means to cause a continuous flow of powdered material in a given plane, a break-up roll having its axis disposed at one side of the path of flow of said material and having one side of its periphery in said path of flow, means to rotate said break-up roll with said side moving in the direction of flow, and means to deliver a current of dry air for directing the broken-up material against the moving surface. 125
22. Apparatus for applying powdered materials to surfaces including means to move a surface in a given path, means to disseminate a powdered material; said disseminating means comprising an endless foraminate belt, a supporting surface for a portion of said belt, means to provide the side-walls of a container above said supporting surface, means to drive said belt, and means to cause the material received by said belt in the openings thereof to fall therefrom at the point where said belt leaves said supporting surface; means interposed in the path of flow of said material for breaking up the same; and means for directing the broken-up material against the moving surface. 130
23. Apparatus for applying powdered material to surfaces, comprising a container, means for supplying a continuous controlled flow of particles of material to the container, means for withdrawing material from the container at a uniform rate, and means for controlling the flow of particles toward a surface and including means for supplying a low velocity particle-guiding current of dry air. 135
24. The method of applying powdered material to a surface, which comprises causing a movement of the surface, directing generally toward said surface a curtain of particles extending transversely of the direction of movement of said surface, and directing against said curtain along a line above said surface a current of dry air moving in a direction transverse to said curtain and toward said surface to alter the course of the particles in the general direction of the current, the course of the finer particles being altered to a greater extent than the course of the coarser particles. 140
25. The method of applying powdered material to a surface, which comprises causing a movement of the surface, directing toward said surface a curtain of particles extending transversely of the direction of movement of said surface, and directing against said curtain along a line above said surface a current of dry air moving at a low velocity in a direction transverse to said stream and towards said surface to alter the course of the particles in the general direction of the current, the course of the finer particles being altered to a greater extent than the course of the coarser particles. 145
26. The method of applying powdered material to a surface, which comprises causing a curtain of particles to be delivered in a given direction, causing a relative movement of said curtain and a surface, and directing a slowly moving dry air current in a direction transverse to said curtain and toward said surface to guide the particles of material to the surface. 150
27. The method of applying powdered material 150

to a surface, which comprises causing a movement of the surface, directing a stream of particles generally toward said surface, and directing a current of dry air against said stream in a direction transverse to said stream and toward said surface and in such manner that the particles will move toward said surface at an angle thereto and will move over a course fan-shaped in cross-section with the heavier particles at the side of the course nearest the point of entry of the air current.

28. Apparatus for applying powdered material to surfaces, comprising means providing a container, means including an endless foraminous belt for withdrawing materials from said container, means to move a surface along a given path, means to remove particles of material from said belt and to direct a stream of the removed particles toward said path, and means to direct an air current against said stream and toward said surface.

29. Apparatus for applying powdered material to surfaces, comprising means to move a surface in a given path, means to cause a transversely extending stream of material to move generally toward said path, a break-up roll interposed in the course of flow of said stream, and means to direct a transversely extended dry air current against said stream immediately below said break-up roll and in a direction transverse to said stream and toward said surface.

30. Apparatus for applying powdered material to surfaces, comprising a measuring device, means to discharge measured amounts of material from the measuring device in a uniform curtain, means to separate any aggregations of particles in the curtain into individual particles, and means to deliver upon the particles a current of dry air so regulated that they will be guided through a free space above a surface and uniformly deposited thereon.

31. Apparatus for applying powdered material to surfaces, including an endless foraminous belt, a member contacting with the underside of said belt and having a transverse edge, means to maintain powdered material above said belt at a point adjacent said member to fill the openings in said belt, the last-mentioned means including a doctor member, means to move said belt past said maintaining means and over said edge, and means disposed beyond said edge in the direction of movement of said belt for vibrating said belt and discharging the powder from the openings therein at a point adjacent said edge.

32. Apparatus for applying powdered material to surfaces, including an endless foraminous belt, a member contacting with the underside of said belt and having a transverse edge, means to maintain powdered material above said belt at a point adjacent said member to fill the openings in said belt, the last-mentioned means including a doctor member, means to move said belt past said maintaining means and over said edge, means disposed beyond said edge in the direction of movement of said belt for vibrating said belt and discharging the powder from the openings therein at a point adjacent said edge, a break-up roll disposed beneath said edge with its axis beyond the same in the direction of movement of said belt, and means to rotate said break-up roll in a direction such that its side under said edge moves downwardly.

33. Apparatus for applying powdered material to surfaces, including an endless foraminous belt,

a member contacting with the underside of said belt and having a transverse edge, means to maintain powdered material above said belt at a point adjacent said member to fill the openings in said belt, the last-mentioned means including a doctor member, means to move said belt past said maintaining means and over said edge, means disposed beyond said edge in the direction of movement of said belt for vibrating said belt and discharging the powder from the openings therein at a point adjacent said edge, a break-up roll disposed beneath said edge with its axis beyond the same in the direction of movement of said belt, means to rotate said break-up roll in a direction such that its side under said edge moves downwardly, means to move a surface in a path under said break-up roll in a direction perpendicular to its axis, and means to direct in a plane just under said break-up roll and in a direction opposite to the direction of movement of its underside and downwardly a current of air having just sufficient velocity to guide the particles toward a moving surface and deposit them thereupon.

34. Apparatus for applying powdered material to surfaces, including means to provide a curtain of powdered material moving in a given direction, a break-up roll disposed in the path of said curtain and arranged to receive the particles on a side thereof moving in the direction of movement of the particles, and means to direct a current of dry air in a plane just under said break-up roll and from the opposite side thereof and downwardly.

35. Apparatus for applying powdered material to surfaces, comprising means for moving a surface along a path, means including an endless belt to provide a curtain of powdered material moving generally toward a surface moving along said path, and means to direct against said curtain a current of air moving in a direction transverse to said curtain and toward said surface and at a speed just sufficient to guide the particles to said surface.

36. Apparatus for disseminating powdered materials, comprising an endless foraminous belt, a supporting surface for a portion of said belt, means to provide the side-walls of a container above said supporting surface, said means including a doctor roller disposed with its periphery adjacent one edge of said supporting member, means to drive said belt, means to drive said doctor roller in a direction such that its periphery moves rearwardly with respect to said endless belt, and means to cause the material received by said belt in the openings thereof to fall therefrom at the point where said belt leaves said supporting surface, said means including a vibrator member.

37. Apparatus for applying powdered material to surfaces, comprising means to cause a transversely extending stream of material to move toward the path of movement of a surface, and means to direct a current of dry air against said stream along a line spaced from said path and in a direction transverse to said stream and toward said path, said directing means being in such position that the air current while moving in said direction contacts the stream before it reaches said path.

38. Apparatus for applying powdered material to surfaces, comprising means to cause a transversely extending stream of material to move toward the path of movement of a surface, and means to direct a low velocity dry air current

against said stream in a direction transverse to said stream and toward said path, said directing means being in such position that the air current while moving in said direction contacts the stream before it reaches said path.

39. Apparatus for applying powdered material to surfaces, comprising an endless foraminate belt, a supporting surface for a portion of said belt, means providing a container from which powdered material may be withdrawn over said supporting surface, a doctor member for limiting the amount of material withdrawn by said belt, and means to cause the material withdrawn by said belt to fall therefrom at a point where said belt leaves the supporting surface, and means to direct a current of air upon the stream of particles after it leaves the belt.
40. Apparatus for applying powdered material to surfaces, comprising an endless foraminate belt, a supporting surface for a portion of said belt, means providing a container from which powdered material may be withdrawn over said supporting surface, a doctor member for limiting the amount of material withdrawn by said belt, means to cause the material withdrawn by said

belt to fall therefrom at the point where said belt leaves the supporting surface, break-up means disposed in the path of movement of the falling particles, and means to direct an air current on the particles after they are acted on by the break-up means.

41. Apparatus for applying powdered material to surfaces, comprising means including an endless foraminate belt for continuously withdrawing quantities of material from a mass, means including a vibrator member for discharging the withdrawn material in a curtain, and means to direct a slowly-moving current of air against the curtain.

42. Apparatus for applying powdered material to surfaces, comprising means to cause a curtain of particles to fall toward the path of movement of a surface, and means for directing a laterally extended current of dry air against one side of said curtain to guide the particles to the surface, said directing means including a restricted ejection channel of substantially uniform extent leading rearwardly from the ejection opening.
